UNITED STATES PATENT OFFICE.

HOWES CROWELL WALLACE, OF SALT LAKE CITY, UTAH.

STATION-INDICATOR.

No. 922,984.

Specification of Letters Patent.

Patented May 25, 1909.

Application filed February 26, 1907. Serial No. 359,412.

To all whom it may concern:

Be it known that I, HOWES C. WALLACE, a citizen of the United States, and a resident of Salt Lake City, in the county of Salt Lake and State of Utah, have invented a new and Improved Station-Indicator, of which the following is a full, clear, and exact description.

My invention relates to station indicators 10 of the general type shown and described in my Patent No. 832,643, of October 9, 1906.

The more particular objects of my improvements are to provide the display mechanism with means whereby it may be operated electrically by the car conductor or other trainman.

My invention further relates to certain details of construction, whereby the general efficiency of the indicator is increased.

Reference is to be had to the accompanying drawings forming a part of this specification, in which similar characters of reference indicate corresponding parts in all the figures.

Figure 1 is a front elevation of the indicator complete and showing at the right the electrical mechanism whereby it is actuated; Fig. 2 is a side elevation of the device as it would appear to an observer stationed to the right of Fig. 1; this view shows particularly the electric switch and the ratchet mechanism controllable thereby for actuating the movable curtain step by step; Fig. 3 is a diagram of the wiring of the system as applied to a car; Fig. 4 is an enlarged fragmentary section showing solenoids, gearing and electric switch, as connected ready for use; Fig. 5 is a side elevation of the armature showing its two magnetic portions connected together by a non-magnetic portion, and also showing diagrammatically the solenoids; Fig. 6 is a fragmentary elevation showing the clutch mechanism and parts immediately associated therewith; Fig. 7 is a fragmentary perspective view showing the snap switch and star wheel for actuating the same.

The frame 5 is provided with an electric bell 6 which may have any desired number 50 of gongs or chime bells for the purpose of creating an alarm. The framework 5 is provided with a column 7 and a rest 8 for supporting certain movable parts. A reel 9 is mounted in the upper part of the frame 55 and adjacent to this reel is a friction spring 10 which bears constantly upon it for the

purpose of exerting a gentle tension upon it so as to prevent it from turning too freely. This reel is provided with a revoluble shaft extending axially through it. A number of rollers 11, 12, 13, 14, 15, 16 extend entirely across the framework. Another reel 17 is mounted in the lower part of the framework. A friction spring 18 presses upon this reel in like manner as the spring 10 presses upon the reel 9, and for the same purpose. A band 19 of cloth or paper is adapted to be wound upon the reels 9 and 17 and to be transferred from the former to the latter, or the reverse, as the reels are turned. This band is provided with intelligible legends 20^a, as indicated in Fig. 1.

Clutch forks 20, 21 are connected with an arm 22 whereby they may be actuated and are supported upon a bracket 22^a. These clutch forks are for the purpose of throwing the reels into and out of action at will. The band 19 is provided with metallic eyelets 23 and the latter are disposed in the same vertical plane as the star wheel 24 which is mounted upon a shaft 24^a, the latter being connected with a snap switch 55. The eyelets are adapted to be engaged by the points of the star wheel in such manner that the travel of the band 19 causes the star wheel to turn step by step. The snap switch is of a well-known kind and comprises contact members 24^b, 24^c, a contact arm 24^d and a spring 24^e. The rotation of the star wheel 24 places the spring 24^e under tension, and when such tension exceeds a predetermined limit, the contact arm releases one of the contact members and engages the other contact arm normally resting upon one or the other of these contact members and being in motion whenever it disengages either contact member. A stay rod 25 extends entirely across the frame and serves to brace and strengthen the latter.

Mounted in the upper part of the frame is a solenoid 26 and in the lower part is a similar solenoid 27. A solenoid core 28 is partly inclosed by the two solenoids. This core is of composite structure, its middle portion being of non-magnetic material, such as brass, while its upper and lower ends are of soft iron. The idea is that the solenoid 26 shall act upon the upper portion of the core and the solenoid 27 shall act upon the lower portion of it, the entire action upon the core as a whole being analogous to that which would take place if there were only a single core of soft iron and a solenoid for attract-

ing the same, with the exception that the lift exerted by the solenoid is considerably greater, owing to the fact that both cores are attracted at the same time.

Extending laterally from the core 28 and secured rigidly thereto is a post 29 carrying at its outer end a pin 30, and upon this pin is mounted a disk or washer 31. An electric switch is shown at 32 and is provided with a switch arm 33 terminating at one of its ends in a link 34 having a slot 35. This slot is of sufficient width to permit lost motion between the link 34 and the pin 30; that is to say, the width of the slot 35 is sufficient to prevent the pin 30 from striking the side walls of the slot or from affecting the link 34 in any other manner than by engaging this link at the ends of the slot.

The switch arm 33 is held upon the switch 32 with sufficient tightness to prevent the switch arm from dropping because of its own weight. In other words, the switch arm 33 normally stays in any position in which it is left, until it is moved positively by the pin 30. The switch 32 is provided with a live contact point 36 and with a dead contact point 37, as will be understood from Fig. 3. A rack bar 38 is connected with the core 28 and engages a gear 39. Mounted upon the latter is a pawl 40 and spring 41, the pawl being pressed by the spring into engagement with a ratchet wheel 42. The ratchet wheel 42 is arranged upon a revoluble shaft 43, and fixed upon this shaft is a gear 44 meshing with a gear 45 upon the shaft 11^a, and a gear 46 upon a shaft 47. The rotation of the gears 45, 46 causes the rotation of the reels 9 and 17.

At 48 (see Fig. 3) is shown a trolley wire 40 for supplying the system with power. At 49 is the trolley of the car upon which the indicator is mounted and supplied with current from said wire. The trolley 49 is connected with a wire 50 by means of a safety cut out 51. From the wire 50 a wire 52 leads to the electric bell 6 and from the latter wires 53, 54 lead to the switch 55 which is operated by the star wheel 24. A wire 56 is connected with the wires 53, 54 and also connected with the solenoid 27, which is connected by a wire 30^a with the live contact point 36. The switch arm 33 is connected by a wire 28^a with the solenoid 26. From the snap switch 55 wires 57, 58 lead to a hand switch 59. This switch has a dead point 59^a and is connected with a wire 60 which is grounded. Wires 61, 62 are connected with wires 57, 58 and lead to another hand switch 63 similar to the hand switch 59. The switch 63 is provided with a dead point 63^a, and also with a ground connection 64.

The purpose of the snap switch 55 is to enable the travel of the band 19 to control the electric current through the solenoids 26, 27, to the extent of shutting off this current

after the band travels a predetermined distance, this distance representing the distance apart of legends upon the band. Supposing the band 19 to be in motion, so that the eyelets 23 turn the star wheel 24, thereby placing the spring 24^e under tension, the switch arm 24^d, being in engagement with a contact point 24^c or 24^b, as the case may be, will not leave the same until the tension of the spring 24^e becomes sufficient to dislodge the switch arm, and when this occurs the switch arm snaps abruptly from one of the contact points to the other. As shown in the drawings, the band 19 travels a sufficient distance for two successive eyelets to engage the star wheel 24 in order to dislodge the switch arm 24^d, and when this occurs the switch arm makes a half revolution. The friction of the switch arm 24^d upon either of the contact points 24^b, 24^c is sufficient to prevent the switch arm from turning, except when the spring 24^e acquires the degree of tension above mentioned.

The hand switches 59, 63 are used independently. When one is in use, the other is so arranged that the circuit to the ground wire is open. For instance, in Fig. 3, by aid of the switch 63 the ground wire 64 is totally disconnected from the wires 61, 62. This is because the switch 59 is being used. If, after reaching the end of the ride and starting back, it be desired to use the switch 63 instead of the switch 59, the latter is moved into such position as to disconnect the wires 57, 58 from the ground wire 60.

My purpose in providing the switches 63 and 59 is to enable the conductor or other trainmen to control the device from either end of the car. The Switches 63 and 59 may, however, if desired, be located at any points intermediate of the ends of the car.

The snap switch 55 is controlled by rotation of the star wheel 24 and this star wheel is turned step by step by aid of the eyelets 23 as the band 19 moves along. The parts are so proportioned and the legends 20^a, 20^b are so spaced upon the band, that each successive position of the snap switch 55 leaves two legends exposed to view, as indicated in Fig. 1. The wires 58, 62 have an office similar to that of the wires 57, 61, and serve to convey the currents approximately half of the time; when the snap switch occupies the position indicated in Fig. 3, so that the current is flowing through the wire 57 and switch 59, the wire 58 is, of course, idle. It remains idle even after the snap switch moves into its contrary position, but in this event the operator, by throwing the switch 59 into its contrary position, may complete the circuit.

The operator, by watching the successive legends as they appear, and learning which of them are associated with one position of the snap switch 55, and which of them are

associated with the opposite position of this snap switch, may, by properly manipulating the switch 59, place the system in such condition that a particular legend 20^b will be 5 displayed.

In manipulating the switch 59 it is obvious that he may sometimes use the wire 57 and sometimes the wire 58. It is equally obvious that when he is at the opposite end 10 of the car, and consequently using the switch 63 he may sometimes employ the wire 61 and sometimes the wire 62.

The operation of my device is as follows: Whenever the car approaches a street or 15 station, the conductor or the trainman closes the circuit by one of the hand switches 59 or 63. If, for instance, the car is going in one direction, the switch used for this purpose is 59. As the train nears the station, 20 the conductor turns this switch into the position shown in Fig. 3, and the following circuit is then completed: Trolley wire 48, trolley 49, safety cut-out 51, to wire 50, whence the current divides and a part 25 passes through wire 52, bell 6 and wire 53, while another part passes through solenoid 26, wire 28^a, switch arm 33, contact button 36, wire 30^a, solenoid 27, wire 56, uniting with the current from wire 53, thence 30 through wire 54, switch 55, wire 57, switch 59; wire 60 to ground. This energizes the solenoids 26, 27 and attracts the core 28, and the rack bar 38 thereupon rises and turns the gear 39. The pawl 40 engages the 35 ratchet wheel 42 and turns it, together with the shaft 43 and gear 44. The latter causes the reels to rotate and the band 19 to move, the direction of such movement being governed by the clutch forks 20, 21 actuated by 40 the clutch arm 22. The core 28, having reached a point just a little below its uppermost position, the pin 30 lodges against the link 34 at the upper end of the slot 35, and turns the switch arm 33 from its position 45 indicated by dotted lines in Fig. 4, to its position indicated by full lines in said figure. This removes the switch arm from the live contact-point 36 and places it upon the dead contact point 37. The circuit is now open 50 and consequently both solenoids are de-energized. The core 28 drops by its own weight. When it reaches such position, the pin 30 lodges against the link 34 at the bottom of the slot 35. The weight and momentum of the core cause the switch arm 33 to turn into the position indicated by dotted lines in this figure. This completes the circuit again, the core again rises, the revolute parts are actuated a second time, 55 the circuit is again broken, the core again 60

drops, and so on as long as the circuit remains closed. A conductor or other officer by moving the hand switch 59 (or 63, as the case may be) thus causes the curtain to move until the name of the station is properly displayed. He then opens the switch 59 (or 63, as the case may be) and when the car approaches another station he repeats the operation, so as to display the name of that station. The switches 59 and 63 are used independently, the switch 59 being employed when the car travels in one direction and the switch 63 being used when the car travels in the opposite direction. When one of these switches is being used 70 the other is thrown out of action by disconnecting the switch arm from both of its contact points or by removing the switch entirely, as desired.

Having thus described my invention, I 80 claim as new and desire to secure by Letters Patent:

1. A station indicator, comprising a plurality of reels, a strip provided with a series of indicating legends, said strip being provided at intervals with eyelets, a gear wheel for each of said reels, an intermediate gear wheel meshing with the other gear wheels so as to actuate the same, a solenoid, a core movable relatively to said solenoid, a rack 85 in connection with said core, a gear wheel meshing with said rack, connections from said last-mentioned gear wheel to said intermediate gear wheel, a switch operated by the solenoid, a star wheel provided with arms adapted to be turned by said eyelets, an electric circuit in connection with said solenoid, a switch for closing said circuit, and means operated by said star wheel for breaking said circuit. 95

2. A station indicator comprising a plurality of reels, a strip provided at spaced intervals with indicating legends and with eyelets, a solenoid, a core within the solenoid, a connection between the core and the reels, 105 whereby the movement of said core will rotate said reels, a star wheel whose arms are adapted for engagement by the eyelets, so as to turn said star wheel, an electric circuit in connection with the solenoid, a manually-110 operated switch for closing the circuit, and means whereby the star wheel may open said circuit.

In testimony whereof I have signed my name to this specification in the presence of 115 two subscribing witnesses.

HOWES CROWELL WALLACE.
